MACHINE COMPANY, OF BOSTON, MASSACHUSETTS, A CORPORATION OF MASSA-
CHUSETTS.

SIDE-LEG CONSTRUCTION FOR MATCHERS AND THE LIKE.

1,406,470.

Specification of Letters Patent. Patented Feb. 14, 1922.

Application filed March 17, 1921. Serial No. 453,189.

To all whom it may concern:

Be it known that I, LOUIS T. MEDHOLDT, a citizen of the United States, and a resident of Winthrop, in the county of Suffolk and 5 State of Massachusetts, have invented an Improvement in Side-Leg Construction for Matchers and the like, of which the following description, in connection with the accompanying drawings, is a specification, like 10 characters on the drawings representing like parts.

This invention relates to wood working machines and the like having rotary cutter heads and the particular application herein 15 shown is to the side leg of a matcher or profiler, that is, the cutter mechanism which is mounted on a more or less upright axis to operate on the edge of a board passing through the machine. The invention relates 20 to an improved arrangement for adjusting and positioning the cutter.

My invention will be best understood by reference to the following description of an 25 illustrative embodiment thereof shown by way of example in the accompanying drawings, wherein:

Fig. 1 is a side view of a portion of a matcher adjacent the side heads with parts in section; and

30 Fig. 2 is a section on the line 2—2 of Fig. 1 with one of the side legs in a different position of adjustment.

Referring to the drawings I have there 35 shown a machine having two staggered side legs 3 and 5 operating on opposite sides of the board passing through the machine and for an understanding of my invention it is sufficient as herein to show the means for 40 positioning and adjusting one of the side legs 5 which in the example shown comprises a rotary cutter head 7 directly driven by an electric motor 9.

In accordance with my invention means 45 are provided for moving the side leg in and out transversely of the machine and also for tilting or swinging the same and conveniently a single operating element is provided for effecting both movements. For this purpose the motor casing 9 may be 50 mounted on a carrier plate 11 on which it may if desired be vertically adjusted by mechanism 13 of well known type, as shown in Fig. 1. The carrier 11 may be mounted, conveniently in the manner hereinafter de-

scribed, on a carriage 15 adapted to slide 55 transversely of the machine on guideway 17. Movement of the carriage on the guideway will effect an in and out adjustment of the side leg. To permit swinging adjustment of the side leg it is mounted pivotally on 60 the carriage 15 and in the embodiment of my invention here shown this mounting is such that the side leg will swing about a point 19 on the work supporting bed corresponding to the inner edge of the cutter head 7 as a 65 center, as shown in Fig. 2, the construction by which this is effected being a subsidiary invention not original with me but in part based on that herein claimed. Referring more particularly to Fig. 1, the carrier 11 is 70 herein mounted on the carriage 15 by means of a depending hook shaped rib 21 on the former, as best shown in Fig. 1, engaging with an arc shaped ledge 23 on the carriage 15, the arc 23 being centered substantially 75 at the point 19. The side leg of the carrier 11 is thus permitted a swinging movement about 19 as a center as 21 is moved along 23.

Suitable means are provided whereby the side leg may be held against either swinging movement or in and out translative movement. Referring to Fig. 1, I will first describe the means whereby the carrier plate 11 is clamped to the carriage 15 to prevent 80 rotative movement. I have herein shown a screw 25 tapped into plate 11 loosely receiving a chock block 27 presented adjacent an edge of the carriage 15, set screws 29 being provided for positioning the block. Mounted on the screw 25 is a cam provided with a 85 hand lever 33 whereby screw and cam can be rotated in such manner as to press the chock 27 inwardly from the position shown in Fig. 1 against the margin of the carriage 15 whereby to clamp the carrier 11 and consequently the side leg thereto so that the side leg will move with the carriage as a 90 unit and not be capable of rotative movement relatively thereto. For locking the carriage 15 to the guide 17 to preclude translative movement of the side head I may provide a locking rod 35 (best shown in Fig. 2) having a squared end extending from the side of the machine by which it may be turned, this locking rod being received between the lower margin of the guideway 17 and the opposed surface of a bracket 37 which extends rearwardly from the carriage 95 100 105

15, the rod being held in position by clip 39 as illustrated. The rod has one side flattened or slabbed off as best illustrated in Fig. 1 and cooperating therewith is an adjusting screw 41 tapped through the bracket 37. When the flattened surface of the rod is interposed between the guideway 17 and the end of set screw 41 there is freedom of movement between the carriage 15 and the guideway 17. When, however, the rod is turned to bring the full diameter thereof between the parts it serves to jam the two together so that the carriage is locked on the guideway and must move as one therewith.

15 A single adjusting mechanism is provided which will serve either to move the side leg in and out or to swing it accordingly as whether one or the other of the cooperative clamping mechanisms is in use. For 20 this purpose a suitable traversing means such as an adjusting screw is connected to the side leg itself at a point remote from the pivot. It will be clearly understood that if the side leg is held against translative 25 movement but is free to swing, movement of the adjusting device will cause it to swing about its pivot. On the other hand, if such pivotal movement is prevented the same force will tend to move the leg bodily. The 30 adjusting device in the present instance takes the form of a screw 43 journaled in the frame of the machine and having an operating portion, such as the squared end shown, projecting at the side thereof. Co- 35 operating with the screw is a nut 45 which, as will be understood, must be rotatively mounted relative to the side leg to permit swinging movement of the latter. In the form of the invention here shown the nut is 40 mounted to slide in an undercut guide 47 in the carriage 15 and has projecting therefrom a pin 49 extending from the face of the carriage and entering a slot 51 in the carrier plate 11, the slot 51, as best shown in Fig. 2, 45 extending transversely of the guideway 47 in carriage 15 which receives the nut. If the clamping bar 35 is in position to lock the carriage 15 on the guide 17 and the clamping chock 27 is released permitting the carrier 11 to swing on the carriage 15 about the arcuate support 23 and the adjusting screw 43 is then turned, the nut 45 will be moved in its guides 47, say toward the reader viewing Fig. 1, and the pin 49, acting on the 55 walls of the slot 51, will swing the side leg to the position shown in Fig. 2. On the other hand, when the parts are in the positions shown in Fig. 1, the clamp 35 is released and the clamp 27 is thrown in, locking the plate 11 to the carrier 15. The nut 45 will be prevented from moving on the guideway 47 since it will be locked by the

engagement of the pin 49 in slot 51 as will be clearly understood from Fig. 2. Therefore, rotation of the screw 43 will move the nut bodily and with it the carriage 15 which will be moved in and out on the guideway 17.

The embodiment of my invention illustrated in the drawing is a construction devised by Percy H. Young of Dorchester, Massachusetts, and certain features of construction shown, representing improvements and refinements of my invention as disclosed by me to him, are not claimed herein as they originated with him.

Having thus described in detail the embodiment of my invention shown by way of example in the accompanying drawings, the principles exemplified thereby which I claim as new and desire to secure by Letters Patent I shall express in the following claims.

Claims:

1. A matcher or like machine having a bed over which work is advanced and a side leg comprising a rotary spindle carrying a revolving cutter head to act on work passing over said bed, a mounting for the spindle providing for translative and swinging movements thereof, means at will to clamp it against one such movement while permitting the other and a traversing means connected to the leg remote from the center of such swinging movement and providing for either translative or angular adjustment of the side leg.

2. A matcher or like machine having a bed over which work is advanced and a side leg comprising a rotary spindle carrying a revolving cutter head to act on work passing over said bed, a single adjusting device therefor and cooperating means to render movement of said device alternatively effective either to traverse the leg or to swing the same to a desired working position.

3. A matcher or like machine having a bed over which work is advanced, a guideway transverse to said bed, a carriage slideable thereon, a support pivoted on the carriage and sustaining a rotary spindle adapted to carry a rotating cutter head for operation on work passing over the bed, releasable means at will to clamp together carriage and guideway, releasable means at will to clamp together carriage and support and an adjusting screw having a nut rotatably associated with the support at a point remote from the pivotal center thereof and providing means for effecting either sliding movement of the carriage or swinging movement of the support.

In testimony whereof, I have signed my name to this specification.

LOUIS T. MEDHOLDT.
